UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,012, dated November 2, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures hereinafter more fully described.

The accompanying photograph illustrates a face view of wall-paper having my new design.

15 Two stripes, A and B, ornamented with a series of rectangular figures like bricks tilted sidewise, inclose the design at top and bottom. On the right and left are vase-shaped figures C C, ornamented with leaf-like projections c c c, and with the suspended rosettes or balls g g.

From each figure C projects a pillar, D, terminating in an Ionic capital, a, and from the shaft of the pillar D, on both sides, project the budding vines b b.

25 Only a portion of the right-hand pillar, D, is shown in the photograph.

The center of the design consists of a group composed of a fan-shaped ornament, E, at the base, set between two figures, F F', which are legs of the birds whose heads are marked with the letters M M.

Above the figure E two wing-like figures, G G, starting from the two whirls H H, meet and cross one another. On either side of these wings G G appears a bird's head, M M, the two heads facing in opposite directions. The breasts of these birds N N are covered with scale-like feathers, which also appear on the wings G G.

40 From the figure E rise bell-shaped ornaments I I, with short stems, and from the middle portion of E rise similar bell-shaped ornaments K K K, with longer stems, and also leaf-like ornaments L L on stems with rectangular bends in them. In the bell-mouths of the figures K K K are the circular half-rosettes e e e. Bell-shaped figures o o also appear near the bases of the vases C C.

45 The design produces a conventional Egyptian-like effect of two birds with their plumage and the incidental ornamentation between

the two ornamented vases and pillars and the upper and lower stripes.

I claim—
